(57) **CLAIM**

I claim the ornamental design for a toy bird whistle, as shown and described herein.

DESCRIPTION

Portions of the disclosure of this patent document contain material that is subject to copyright protection. The copyright owner has no objection to the facsimile reproduction by anyone of the patent document or the patent disclosure as it appears in the Patent and Trademark Office file or records, but otherwise reserves all copyright rights whatsoever.

FIG. 1 is a left side view of a toy bird whistle according to the new design.

FIG. 2 is a front view of said toy bird whistle according to the new design.

FIG. 3 is a right side view of said toy bird whistle according to the new design.

FIG. 4 is a rear view of said toy bird whistle according to the new design.

FIG. 5 is a vertical, longitudinal sectional view, taken along the line 4-4 of FIG. 1.

FIG. 6 is a top view of said toy bird whistle according to the new design.

FIG. 7 is a left side perspective view of the toy bird whistle according to the new design.

FIG. 8 is a left side perspective view of the toy bird whistle with the beak portion separated from a tail section, according to the new design.

FIG. 9 is a rear view of the beak portion of the toy bird whistle according to the new design.

FIG. 10 is a rear view of the tail section of the toy bird whistle according to the new design; and,

FIG. 11 is a right side perspective view of the toy bird whistle according to the new design.

The broken line showing of a face is included for the purpose of illustrating portions of the "article" and forms no part of the claimed design.
